DESIGN FOR A PHOTOGRAPHIC REPRODUCTION UNIT

John B. Tupper, Upper Montclair, N. J.

Application May 23, 1940, Serial No. 92,537

Term of patent 7 years

To all whom it may concern:

Be it known that I, John B. Tupper, a citizen of the United States, residing at 10 Bradford Avenue, Upper Montclair, in the county of Essex and State of New Jersey, have invented a new, original, and ornamental Design for a Photographic Reproduction Unit, of which the following is a specification, reference being had to the accompanying drawing, forming part thereof.

Figure 1 is a perspective view, and Figure 2 is a side elevational view of the photographic reproduction unit showing my new design the back and the opposite side being plain.

I claim:

The ornamental design for a photographic reproduction unit, substantially as shown and described.

JOHN B. TUPPER.
